UNITED STATES PATENT OFFICE.

DAVID FISHER, OF PADEN CITY, WEST VIRGINIA, ASSIGNOR TO PADEN CITY GLASS
MANUFACTURING COMPANY, OF PADEN CITY, WEST VIRGINIA, A CORPORATION
OF WEST VIRGINIA.

DESIGN FOR AN ASH TRAY.

Application filed May 20, 1926. Serial No. 17,776. Term of patent 7 years.

To all whom it may concern:

Be it known that I, DAVID FISHER, a citizen of the United States, residing at Paden City, West Virginia, have invented a new, original, and ornamental Design for an Ash Tray, of which the following is a specification, reference being had to the accompanying drawings, forming a part thereof.

The drawing is a perspective view of an ash tray showing my new design.

I claim:

The ornamental design for an ash tray, as shown.

DAVID FISHER.
